UNITED STATES PATENT OFFICE

WENDELL L. CARLSON, OF SCHENECTADY, NEW YORK, ASSIGNOR TO GENERAL ELECTRIC COMPANY, A CORPORATION OF NEW YORK

AMPLIFYING SYSTEM

Application filed May 13, 1925. Serial No. 30,036.

My present invention relates to electrical communication, and more particularly to amplifying systems employed in the reception of electrical signals.

5 This application is a continuation in part of my prior application, Serial No. 589,726, filed September 21, 1922, Patent 1,649,098.

An object of my invention is to provide a compact arrangement of the apparatus required in an amplifying system involving the 10 use of a plurality of amplifying valves.

Another object of my invention is to provide a construction for amplifying systems whereby the manufacture may be simplified 15 and the cost reduced.

My invention is especially adapted to a radio frequency amplifying system, and will be described herein in connection with such a system, but it is to be understood that it is 20 also applicable to a system for amplifying audio frequency currents.

Heretofore it has been customary to construct individual transformers for each stage of a thermionic cascade amplifier and mount 25 them so that they will be separated by substantial distances. I have found, however, that it is possible to assemble the various transformer windings of a cascade amplifier all on a single iron core shell in such a way 30 that part of the iron magnetic path will be common to adjacent sets of windings without introducing operating difficulties due to feedback of energy from one circuit to a preceding circuit. In cases where the amplifier is desired to operate over an extremely wide range 35 of frequencies, the individual windings of the transformer units may be designed differently though assembled on one shell, and the leads connected to a suitable switch so as 40 to connect alternately the proper transformer with the amplifier circuit to operate on the particular frequency range for which it is designed.

The novel features which I believe to be 45 characteristic of my invention are set forth with particularity in the appended claims. My invention itself however both as to its organization and method of operation will best be understood by reference to the following description taken in connection with the

accompanying drawings in which Fig. 1 shows diagrammatically a radio receiving circuit employing three radio frequency stages of amplification and a detector. Fig. 2 shows diagrammatically a radio receiving circuit employing one radio frequency stage of amplification and a detector tube, and three radio frequency transformers, each designed to operate over a different frequency range. Fig. 3 is a plan view of three radio frequency transformers mounted on a single iron core which are adapted to be employed in the circuits shown in Figs. 1 and 2; and Fig. 4 is a diagrammatic representation of a superheterodyne radio receiving system showing one high frequency transformer and three intermediate frequency transformers mounted on a single iron core.

In the arrangement shown in Fig. 1 the tuned antenna circuit 1 is coupled to a secondary tuned circuit 2, which in turn is connected to the input of an electron discharge amplifier 3. The output of amplifier 3 is coupled by the radio frequency transformer 4 to the input of amplifier 5. The output of 70 amplifier 5 is in like manner coupled to the output of the third amplifier 7 by a coupling transformer 6. Transformer 8 couples the output of amplifier 6 to the input of a detector 9 which has a telephone receiver 10 connected 75 in its output circuit.

In the arrangement of Fig. 2 the antenna 80 1 is coupled to the secondary tuned circuit 2 which is connected to the input of the electron discharge amplifier 3. The plate lead of amplifier 3 is connected to the switch arm 11 which is adapted to make contact with points 12, 13 and 14 as the arm is rotated at the will of the operator. In like manner, the switch arm 15 may be rotated 85 simultaneously with arm 11 to make contact with points 16, 17 and 18. The primary windings of transformers 19, 20 and 21 are connected at one end to contact points 12, 13 and 14, and the other ends, known as the 90 low potential terminals, are connected to a common terminal and to the plate battery 22. The secondary windings of transformers 19, 20 and 21 are connected at their high potential ends to points 16, 17 and 18 and 100

their low potential ends are commonly connected to the cathode of detector 9.

In the transformer arrangement shown in Fig. 3 the radio frequency transformers 4, 5 and 8 of Fig. 1, or 19, 20 and 21 of Fig. 2, are indicated in the manner in which they may be mounted in the transformer unit. Each individual transformer has its own primary and secondary winding wound on a small laminated iron core plug 23. The laminated iron shell 24 having legs 25 completes the magnetic path around the coils, forming what are generally known as shell type transformers. Air gaps 26 are preferably provided between the core plugs 23 and the shell 24 in order to reduce the iron losses and regulate the permeability of the magnetic path.

The operation of the system shown in Fig. 1 is so well known in the art that it is not necessary to dwell on it extensively here, it being sufficient to say that the radio carrier wave of the incoming signal is amplified by means of the three amplifiers 3, 5 and 7, and that the modulating component of the carrier frequency actuates the telephone receiver 10 due to the rectifying action of detector 9. It has heretofore been believed that the magnetic coupling between adjacent individual transformers in such a construction as that herein disclosed, would create local oscillations in the accompanying amplifier circuits. I have found, however, that the stray magnetic coupling existing with such a transformer construction on short wave lengths is practically negligible so far as the creation of local oscillations is concerned. If on low radio frequencies or audio frequencies it is found that due to the greater penetration of the field in the iron the coupling between the adjacent individual transformers creates troublesome effects, then by properly connecting the adjacent windings of the transformers, i. e. all windings in the same directions, the oscillating tendency of the system will be eliminated.

The operation of the system shown in Fig. 2 is identical to the operation of the circuit shown in Fig. 1 except that only one amplifier 3 is employed in conjunction with the individual transformers 19, 20 and 21, and detector 9. The individual transformers 19, 20 and 21 are designed to cover different wave length ranges, i. e., they differ in construction and number of turns, and air gaps 26 between the shell 24 and plugs 23, by switching to the proper transformer good amplification can be obtained over the range which the transformer is designed to cover. While only one radio stage is shown in this case, it is obvious that any practical number of stages and a corresponding number of transformer units may be employed.

In the super-heterodyne system shown in

Fig. 4 I have indicated a radio amplifying tube 27 to the input circuit of which received signals are supplied from a tuned loop 28. The output of tube 27 includes a primary 29 of a radio frequency transformer, which is mounted on a plug 30 and coupled to a secondary winding 31, which is included in the input circuit of detector tube 32. Local oscillations from an oscillator tube 33 are also supplied to this input circuit of detector tube 32 through the coupling transformer 34.

By the means thus far described, currents of a frequency lower than that of the received currents are supplied to the primary winding 35 of an intermediate frequency transformer 36. The secondary 37 of this transformer is connected to the input of an amplifier 38 and the output circuit of 38 in turn includes the primary winding 39 of a second intermediate frequency transformer 40. The secondary 41 of transformer 40 is connected to the input of a second intermediate amplifier 42, the output of which in turn includes the primary 43 of the third intermediate frequency transformer 44. The secondary 45 of intermediate transformer 44 is connected to the input of detector 46.

I have found it desirable in the arrangement described to employ magnetic shunts 47 for the first two intermediate frequency transformers to reduce the coupling between primary and secondary windings. Air gaps of suitable dimensions may be provided between the plugs 30 and 48 upon which the transformers are wound and the shell 49.

In order to prevent the tendency for production of oscillations in the intermediate frequency amplifying tubes by reason of capacity feed-back, the windings of the successive intermediate frequency transformer may be so located as to provide a magnetic feed-back from the output circuit of tube 42, for example, to the input circuit, to counteract the capacity feed-back through the tube. Since the intermediate frequency transformers are intended to be operated at a single frequency a neutralization of the oscillation tendency produced in this way can be affected which is correct for any signaling frequency which may be received.

It will of course be understood that the circuit arrangement shown in Fig. 4 is purely diagrammatic and includes only the essential parts of the circuit in order to simplify the drawings. Yet in practice many modifications may be made in the circuit, such for example, as the provision of common A and B batteries for all of the tubes, and in some cases, condensers for tuning the various windings if desired. Such modifications, however, do not affect the fundamental structure of the common transformer unit.

What I claim as new and desire to secure by Letters Patent of the United States, is:

1. The combination in an amplifying system of a plurality of electron discharge amplifiers connected in cascade and an iron core having mounted thereon a plurality of sets of transformer windings, said transformer windings serving to connect the output circuits of a plurality of amplifiers to the input circuits of a plurality of amplifiers, at least one of said amplifiers being connected to 5 amplify radio frequency currents of a received signaling frequency and another of said amplifiers being connected to amplify currents of a different frequency.
2. The combination in an amplifying system of a plurality of electron discharge amplifiers connected in cascade and an iron core having mounted thereon a plurality of sets of transformer windings, said transformer windings serving to connect the output circuits of a plurality of amplifiers to the input circuits of a plurality of amplifiers, at least one of said amplifiers being connected to amplify radio frequency currents of a received signaling frequency and another of said 10 amplifiers being connected to amplify currents of a different radio frequency which is lower than that of the received signaling currents.
3. The combination in an amplifying system of a plurality of electron discharge amplifiers connected in cascade and an iron core having mounted thereon a plurality of sets of transformer windings, said transformer windings serving to connect the output circuits of a plurality of amplifiers which are connected to amplify radio frequency currents of a lower frequency from that to be received, to the input circuits of a plurality 15 of amplifiers.
4. The combination in an amplifying system of a plurality of electron discharge amplifiers connected in cascade and an iron core having mounted thereon a plurality of sets of transformer windings, said transformer windings serving to connect the output circuits of a plurality of amplifiers to the input circuits of a plurality of amplifiers certain of said transformer windings being so related to other of said transformer windings 20 as to provide a magnetic coupling from one output circuit to a preceding input circuit which opposes the effect of other couplings between said circuits.
5. The combination in an amplifying system of a plurality of electron discharge devices connected in cascade and an iron core having mounted thereon a plurality of sets of transformer windings, one set of said windings serving to connect the output circuit 25 of an amplifier which is adapted to amplify received signaling currents of radio frequency to the input circuit of a detector and a plurality of other sets of windings serving to connect the output circuits of a plurality of amplifiers which are connected to amplify 30
- radio frequency currents of a lower frequency than that received, to the input circuits of a plurality of amplifiers.
6. The combination in an amplifying system of a plurality of electron discharge amplifiers connected in cascade, and transformer means for connecting the output circuits of a plurality of said amplifiers to the input circuits of a plurality of said amplifiers comprising a shell of magnetic material having 35 a plurality of parallel legs, a plurality of sets of transformer windings mounted on cores which are inserted between adjacent parallel legs, and a magnetic shunt interposed between the primary and secondary winding of at least one set of said windings.
7. The combination in an amplifying system of a plurality of electron discharge amplifiers connected in cascade, and transformer means for connecting the output circuits of a plurality of said amplifiers to the input circuits of a plurality of said amplifiers comprising a shell of magnetic material having 40 a plurality of parallel legs, a plurality of sets of transformer windings mounted on cores which are inserted between adjacent parallel legs, adjacent sets of said windings being arranged to provide a magnetic coupling from the output circuit of one amplifier to a preceding input circuit which opposes the effect of other couplings between the circuits.
8. In combination, a plurality of electric discharge devices adapted to be connected in tandem, an inter-stage transformer having a primary winding connected to the output electrodes of one of said devices and a secondary winding connected to the input electrodes of another of said devices, a core structure for said inter-stage transformer, an input transformer for said first device, a core structure for said input transformer having a leg in common with the core for said inter-stage transformer, an output transformer for 50 said second device and a core structure for said output transformer having a leg in common with the core for said inter-stage transformer.
9. In combination, a vacuum tube having input and output terminals, an inductive winding connected to said input terminals, a second inductive winding connected to said output terminals, a core and magnetic circuit for one of said windings, a different core and different magnetic circuit for the other 55 said winding, and means for passing a portion only of the flux in the second inductive winding through the first inductive winding.
10. In combination, a vacuum tube having input and output terminals, an inductive winding connected to said input terminals, a second inductive winding connected to said output terminals, a core and magnetic circuit for one of said windings, a different core and different magnetic circuit for the other 60

said winding, and means comprising a portion common to the two core structures to provide coupling between said windings.

11. In combination, a vacuum tube having
6 input and output terminals, an input transformer whose secondary is connected to said input terminals, an output transformer whose primary is connected to said output terminals, means for causing a portion only of the
10 flux in the primary of the output transformer to pass through the secondary of the input transformer.

12. A combination according to the preceding claim in which said transformers are of
15 the shell type and in which the means for causing a portion only of the flux in the primary of the output transformer to pass through the secondary of the input transformer comprises an intermediate flux carrying member which is common to the magnetic circuits of both transformers.

13. In combination, a transformer comprising a primary coil and a secondary coil and a core member extending therethrough,
25 a second transformer comprising a primary coil and a secondary coil and a second core member extending therethrough, a first member of magnetic material extending around said transformers and cooperating with one
30 end of each of said cores for the passage of flux, a second member of magnetic material cooperating with the other end of each of said cores and with said first member of magnetic material for the passage of flux whereby there is a different magnetic circuit for each transformer, with the second magnetic member common to both of said circuits, and a portion only of the flux in
35 one of the cores passes through the other core.

40 In witness whereof, I have hereunto set my hand this 11th day of May, 1925.

WENDELL L. CARLSON.
